UNITED STATES PATENT OFFICE.

ANDRE JANER, OF FLUSHING, NEW YORK.

KEYLESS LOCK.

Application filed March 29, 1926. Serial No. 98,089.

This invention relates to locks, and more particularly to keyless locks of the type known as permutation locks, in which a pre-determined sequence of operations is required to be performed in order to open the lock, and contemplates more particularly a lock of the class described having pins projecting outwardly from the face plate, which pins may be located by sense of touch. After the pins have been located the lock may be operated by sense of touch, aided if desired by the ear.

A lock constructed in accordance with my invention includes many desirable features, among which may be mentioned the following:—

It may be opened in the dark; it is practically impossible for an unauthorized person to open it by "ringing the combination" because of the large number of possible permutations which may exist and the time necessary to set up each permutation; it cannot be opened by an unauthorized person by feeling for the openings in the locking disc by exerting pressure on the unlocking knob and operating the locking discs, nor by listening for the clicks of the mechanism; and in case the combination to which the lock is set becomes known, it may be changed to open only to a different combination.

The features of novelty which I believe to be characteristic of my invention are set forth with particularity in the appended claims. My invention itself however, both as to its fundamental principles and as to its practical embodiment will best be understood by reference to the specification and accompanying drawing, in which

Figure 1 is a side elevation of a lock according to my invention, showing the side away from the bolt.

Figure 2 is a front elevation thereof.

Figure 3 is a top plan view.

Figure 4 is a bottom plan view.

Figure 5 is a side elevation of the lock looking toward the bolt side.

Figure 6 is a section on line 6—6 of Figure 5.

Figure 7 is a longitudinal section along lines 7—7 of Figure 8.

Figure 8 is a transverse section along lines 8—8 of Figure 7.

Figure 9 is a section on line 8—8 of Figure 7 but showing the parts just after the lock has been set to zero.

Figure 10 is a detail of modified ratchet mechanism; and

Figure 11 is a detail of the face plate and operating pins of the modified form shown in Figure 10.

Referring now more particularly to Figure 1, the lock according to my invention comprises a face plate 1, and a rear plate 2 held in spaced relation by cross members 3 secured thereto in any suitable manner as for instance by bolts 4. A suitable end plate 5 may also be provided secured in any suitable manner to prevent access to the mechanism of the lock. Latch 6, which may be of the conventional type if desired, is formed on shank or bar 7, the latch 6 and shank 7 together forming the bolt, and shank 7 is slidably supported by arms 8 (Fig. 3) projecting from rear plate 2. In order to permit of latch 6 being withdrawn from the rear side of the lock, an upwardly and laterally projecting piece 9 is secured upon the shank 7 of the bolt, for example by means of screw 10 (Fig. 8). The member 9 projects laterally and upwardly from the shank 7 in the path of cam member 11 mounted upon stub shaft 12 carried in sleeve 13 secured to the rear plate 2. Cam 11 is secured in position by any suitable means such as set screw 14, engaging shaft 12, and shaft 12 in turn is provided with a suitable handle 15 for operating it. The handle 15 may conveniently be formed integral with the shaft by bending the shaft and flattening it.

Referring now particularly to Figures 7 and 8 it will be seen that the bolt may be withdrawn by operation of handle 15, which in turn operates cam 11, the face of which engages with projecting member 9 to withdraw the bolt. The bolt is returned to projected position when the handle 15 is released through the action of suitable restoring means such as spring 16, secured for example to member 9 and to support 8. The contraction of this spring restores the bolt to projected position and likewise restores handle 15 to its corresponding position after release.

It is to be noted at this point that the action just described is quite independent of whether the lock is or is not released. In other words it is always possible to release the bolt from the rear side of the lock regardless of whether the lock is set.

For the purpose of withdrawing the bolt

under the control of the permutation locking discs there is provided a projection 17 extending upwardly from shank 7 of the bolt. In the form shown this projection is constituted by a screw passed through the shank of the bolt and extending upwardly. Projection 17 is engaged by laterally extending projecting member 18 mounted upon locking bar 19 and carried thereby (Fig. 3). The locking bar 19 is itself actuated by a laterally extending projection 20 carried thereby which is engageable by a cam member 21 mounted upon and operated by shaft 22 supported for example, by rear bearing 23 and passing through the face plate 1 and terminating in operating knob 24. Cam 21 is fixed in proper position by suitable means, such as set screw 28.

It will now be seen that if the locking discs do not interfere with the movement of the locking bar, rotation of the knob 24 in a counter clockwise direction will cause cam 21 acting upon projection 20 to force the locking bar to the left as shown in Figure 7, carrying with it projection 18 which engages projecting projection 17, in the shank 7 of the bolt, and thereby withdraws the bolt from engagement with the casing.

For a purpose which will later be described a collar 25 is shown mounted upon shaft 22 and secured in position by means of set screw 26, the collar being provided with a projection 27, (Figs. 4 and 6).

For the purpose of controlling the operation of bolt by means of knob 24 I have provided permutation locking mechanism supported as a whole by cross members 30 extending between front and rear plates 1 and 2, (Figs. 4, 7 and 8). Journaled in these cross members 30 I have provided a shaft 31 mounted in a cut-out portion of the cross members and secured therein by blocks 32 which in turn are held in position by suitable means such for example as screws 33 passing through cross members 30 and engaging blocks 32.

Mounted upon this shaft 31 I have provided three locking discs 34, 35, and 36, respectively, operating in locking notches 37, 38 and 39 of locking bar 19, (Fig. 7). Each of these locking discs is provided with a cut-out portion 40, 41 and 42 respectively, of just sufficient width and depth to permit the passage of locking bar 19 therethrough, as will be seen from Figure 8. It is clear that in order to operate the bolt by means of handle 24, locking discs 34, 35 and 36 must be lined up so that their openings 40, 41 and 42 are in registry with locking bar 19.

When this is the case the locking discs will not interfere with the operation of locking bar 19 and the bolt may be withdrawn as already described by turning knob 24. If the locking discs are not in registry as described, movement of the locking bar 19 can-

not take place and consequently the bolt cannot be withdrawn by operation of knob 24.

In order to permit the lining up of the locking discs with their openings in proper registry I have provided three ratchet discs 43, 44 and 45, one for each of the locking discs and suitably secured thereto by means of screws 87, 88 and 89. The ratchet discs 43, 44 and 45 are provided with ratchet teeth as will be seen by reference to Figures 5, 8 and 9 adapted to be engaged by pawl members 46, 47 and 48.

Mounted upon the shaft 31 are three discs 58, 59, and 60 each mounted adjacent a ratchet disc with spacing members interposed if desired, and each of these discs is provided with a downwardly extending arm. That arm on the disc 58 being indicated at 49 in Figure 5 and the arm on the disc 60 being shown in Figures 8 and 9 at 51, the arm on the disc 59 not being visible in the position assumed by the parts as illustrated in any of the figures. It is upon these arms that the pawls are pivotally mounted as at 55, 56 and 57. Each of the pawls is biased toward its ratchet wheel by suitable springs such as is shown at 54 in Figure 8 respectively and each of the discs is provided on the opposite side with outwardly extending arms 61, 62 and 63 projecting through the face plate 1, which is provided with suitable slots 64, 65 and 66 so that arms 61, 62 and 63 may be depressed to operate the ratchet wheels and thereby rotate the locking discs. Spring members 70, 71 and 72 are provided secured to the rear plate 2 and arranged to exert pressure on pawl members 46, 47 and 48 on the opposite sides of the pivot so as to maintain the pawl members normally out of contact with the teeth of the ratchet members so that the ratchet discs may be rotated in the opposite direction to that imparted by the pawls by means to be described hereafter. The arrangement of spring members 70, 71 and 72 is such that downward movement of the arms 61, 62 or 63 causes upward movement of the pawl mechanism which permits the less powerful springs such as spring 54 to force pawls 46, 47 or 48 into engagement with a ratchet tooth. Further depression of the arm will therefore move the ratchet disc through a distance of one tooth, in a counter clockwise direction, carrying with it the locking disc. Suitable springs 67, 68 and 69 return the arms to initial position upon release. From the foregoing it will be evident that by depression of the proper arm the desired number of times, any ratchet disc and its associated locking disc may be turned through any number of degrees as desired, each independently of the other.

Referring now to Figure 10 I have shown a modified form of ratchet disc which has certain advantages. The ratchet disc 45'

is shown as having three times the number of teeth as on ratchet disc 45 whereby a complete downstroke of arm 63' will move ratchet disc 45' through a distance of three 5 teeth. For the purpose of utilizing the advantages which this construction makes possible, I have provided three notches 119, cut in each of the slots 64', 65' and 66' and a co-operating ridge or projection 120 on each 10 of the arms 61', 62', and 63'. Each arm may therefore be operated either one-third or two-thirds of a stroke or a complete stroke, thereby moving the ratchet disc and the locking disc over a distance of one, two 15 or three ratchet teeth, which greatly increases the number of possible permutations obtainable.

From the foregoing it will be understood 20 that the position of the locking discs may be controlled by the operation of arms 61, 62 and 63. It will also be understood that when the lock is set to zero, or in other words, when all of the locking discs have a predetermined position with reference to each 25 other, and to locking bar 19, the discs may be arranged with their openings in registry with the locking bar to permit opening the lock, by operating each of the arms the number of times required to move the particular locking disc controlled thereby into 30 a position such that its opening registers with the locking bar. Some means must be provided for setting the lock to zero or starting position so that the proper number of 35 operations of each of the arms will cause the openings in the locking discs to register with the locking bar. These means will now be described.

Referring particularly to Figure 7 I have 40 shown three discs 75, 76 and 77 provided with gear teeth around their peripheries. Each of these discs has a section of its teeth cut away as at 80 as will be more particularly seen from Figure 1. Each of the locking 45 discs 34, 35 and 36 is provided with a row of holes 81, 82 and 83 (Fig. 9) adapted to receive pins 84, 85 and 86 (Fig. 7) which extend through gear discs 75, 76 and 77 into the locking discs 34, 35 and 36, thereby fixing 50 the position of the locking discs with reference to the gear discs. The number of operations of arms 61, 62 and 63 which will be required to set the locking discs with their 55 openings in registry will depend upon the relative position of gears 75, 76 and 77 with reference to their locking discs 34, 35 and 36, as will be more clearly explained hereafter. The entire ratchet, locking disc, and gear disc assembly is secured in proper position upon the shaft 31 by means of a washer 90 interposed at one end between gear disc 77 and support 30 and spring 91 interposed at the other end of shaft 31 between disc 58 60 and support 30. Spacer members such as 65 washers 92 may be interposed between the

discs as desired. For engagement with the gear discs 75, 76 and 77 I have provided three gear discs 93, 94 and 95 (Figs. 4 and 9) mounted upon shaft 96 and suitably secured thereto as by keying so as to be rotated by 70 the rotation of shaft 96. Shaft 96 is carried in a suitable yoke member 97 pivotally supported as at 98 from rear plate 2 and provided with an arm 99 extending through the slot 100 in the face plate 1. To prevent access to the interior of the locking mechanism a sliding plate 101 may be provided engaging or surrounding member 99 and pressed against the rear of face plate 1 by a suitable spring 102. To maintain the yoke 80 75 in proper position a support 103 (Fig. 1) may be provided secured to support 30 and provided with a projection adapted to prevent yoke 97 from moving too far and having attached thereto spring means 104 for 85 biasing gears 93, 94 and 95 out of engagement with gears 75, 76 and 77. Mounted upon shaft 96 at one end thereof I have provided a bevel gear 105 adapted to be operated by a second bevel gear 106 mounted 90 upon shaft 107 provided with a thumb nut or other operating means 108 in front of the face plate 1.

From the foregoing it will be understood 95 that rotation of thumb nut 108 will rotate gear 106 and thereby gear 105 which will in turn rotate shaft 96 and gears 93, 94 and 95. If arm 99 is pressed upwardly against the action of its spring bias, gears 93, 94 and 95 may be engaged with gears 75, 76 and 77 100 and each of these gears will therefore be rotated until the blank section or the mutilated portion of the gear disc has been brought into engagement with gears 93, 94 and 95. At this point no further rotation 105 of gears 75, 76 and 77 can take place under the action of thumb screw 108 and the lock is set to zero and ready to be opened by operating the arms 61, 62 and 63 according to the known combination.

It is sometimes possible for expert thieves 110 to open a permutation lock by exerting pressure upon the knob in a direction to withdraw the bolt and then operating the combination to determine by sense of touch when the locking disc openings are in registry with the locking bar. To prevent the possibility of a lock according to my invention being opened in this way by unauthorized persons I have provided means for 115 preventing operation of the arms 61, 62 and 63 or any one of them whenever pressure is applied against handle 24 in a direction to withdraw the bolt. As a matter of fact it is necessary to turn handle 24 in the opposite direction to that required to withdraw the bolt when it is desired to operate arms 61, 62 and 63. The means which I have provided for this purpose will now be 120 described.

Referring now to Figure 6 I have shown a plate member 109 having three L-shaped slots 110 formed therein. Suitable brackets 111 and 112 are provided on the rear of face plate 1 for slidably mounting plate 109. Plate 109 is formed with a projecting portion 113 adapted to be engaged by projection 27 on collar 25 of shaft 22. Plate 109 is likewise provided with a rearwardly extending projection 114 adapted to be engaged by suitable spring 115 which biases plate 109 to the right as shown in Figure 6. From the foregoing it will be seen that the slots 110 in plate 109 are normally out of registry with the slots 64, 65 and 66 in face plate 1 and that arms 61, 62 and 63 cannot be operated while the slots are not in registry. In order to be able to operate the arms 61, 62 and 63 it is necessary to rotate handle 24 in a clockwise direction as viewed in Figure 2 which causes projection 27 to engage with the part 113 of plate 109 and force the plate to the left in Figure 6 until slots 110 are in registry with slots 64, 65 and 66. The arms 61, 62 and 63 may then be operated to set the combination and handle 24 may then be rotated in a counter clockwise direction to withdraw the bolt.

To prevent rotation of thumb screw 108 in an improper direction I have provided ratchet member 121 mounted upon shaft 107, the end of which may be fixed in position by yoke member 123. A suitable spring member 122 is provided for engagement with ratchet member 121. For the purpose of producing clicks which may serve as an indication when operating the combination of my lock in the dark I have provided three springs 116 mounted upon a cross member 117 secured to supports 30 and held in position thereon by yoke member 118 secured to cross member 117 by any suitable means such as bolts.

The construction of a lock according to my invention having been described, it is believed that the operation thereof will be readily understood. Assuming that the bolt is in locking position and that the locking discs are neither at zero position nor in unlocking position, if it is desired to open the lock, arm 99 will be pressed upwardly to engage the gears carried on yoke member 97 with the gears carried on shaft 31. Rotation of thumb nut 108 will then rotate each of the gears 75, 76 and 77 to a position where the mutilated sections are lined up in registry and directly opposite the gears 93, 94 and 95. Since locking discs 34, 35 and 36 are secured to gears 75, 76 and 77 by pins 84, 85 and 86 the locking discs will be carried with the gear discs and will be arranged each having its opening a certain distance from the locking bar and it will be known how many operations of each of the arms 61, 62 and 63 are required to cause each

of the locking discs to register. Assuming for example that locking disc 34 when in zero position requires to be turned through a distance equivalent to six teeth of ratchet disc 43, arm 61 will be pushed downward to the full extent of its motion six times thereby causing locking disc 34 to take a position with its opening in registry with the locking bar. Similarly the other discs will be rotated to proper position by the operation of arms 62, and 63 after which knob 24 may be rotated to withdraw the bolt. To reset the lock, it is only necessary to press arm 99 to engage the gears on yoke 97 with the gears on shaft 31, and rotate thumb nut 108 to change the position of the locking discs.

It will be understood that if the combination should become known to unauthorized persons the lock may be rearranged to open to a different combination by removing shaft 31, disassembling the permutation mechanism and changing the position of any one of the locking discs 34, 35 and 36 with reference to its associated gear disc 75, 76 and 77 or the relation of each of these. This may be done simply by withdrawing pins 84, 85 and 86, shifting the position of the gear with respect to the locking disc, and returning the pin to secure the locking disc to the gear in its new position.

While I have shown and described certain forms of my invention, it will be understood that modifications and changes may be made without departing from the spirit and scope thereof, as will be apparent to those skilled in the art.

Having described my invention, I declare that what I claim is:

1. In a permutation lock, a bolt, means operable from the rear of said lock to withdraw said bolt independently of the locking mechanism, a locking bar mounted for longitudinal sliding movement, means associated therewith for withdrawing the bolt on predetermined movement of said locking bar, means operable from the face of said lock for withdrawing said bolt under control of the locking mechanism and means normally preventing the operation of said last named means.

2. In a permutation lock, a bolt, means operable from the rear of said lock to withdraw said bolt independently of the locking mechanism, a locking bar, means associated therewith for withdrawing said bolt on predetermined movement of said locking bar, means operable from the face of the lock for moving said locking bar under control of the permutation mechanism and means normally preventing the operation of said last named means.

3. In a permutation lock having a plurality of locking discs, in combination,

- means operable from the face of said lock for withdrawing the bolt under control of the permutation mechanism, means for setting each of said locking disks to unlock-
 5 ing position and means operable from the face of said lock for setting said locking disks to zero and normally disconnected therefrom.
4. In a permutation lock having a plu-
 10 rality of locking discs, in combination, means operable from the face of said lock for setting each of said discs to unlocking position, means operable from the face of said lock for setting said discs to zero, and
 15 normally operatively disconnected therefrom, and means operable from the face of said lock for operatively connecting said means and said discs.
5. In a permutation lock having a plu-
 20 rality of locking discs, in combination, a face plate having slots therein, a plurality of pins extending through said slots for movement therein and operatively associated with said locking discs, and means for
 25 normally preventing operation of said pins.
6. In a permutation lock having a plu-
 30 rality of locking discs, in combination, a face plate having slots therein, a plurality of pins extending through said slots for movement therein and operatively associated with said locking discs, means for normally preventing operation of said pins, means operable from the face of said lock for withdrawing the bolt, and means controlled thereby for releasing said pins for
 35 operation.
7. In a permutation lock, in combination, a shaft, a plurality of locking discs arranged coaxially thereon, a face plate parallel to the axis of said shaft, and provided with slots, and pins rotatably mounted upon the shaft and extending through said slots for substantially translational movement therein, and means operatively connecting each of said pins to a locking disc.
8. In a permutation lock, in combination, a locking disc, a ratchet disc secured thereto, a mutilated gear, and means for operatively securing said disc and said gear in desired angular relation.
- 50 9. In a permutation lock, in combination, a shaft, a locking disc thereon, a ratchet disc secured to the disc, pawl mechanism for operating said ratchet disc, a face plate having a slot therein, and an arm pivoted upon the shaft and projecting through said slot and carrying said pawl mechanism.
10. In a permutation lock, in combination, a shaft, a locking disc thereon, a ratchet disc secured to the disc, pawl mechanism for operating said ratchet disc, a face plate having a slot therein, an arm rotating about the shaft and projecting through said slot and carrying said pawl mechanism, and said ratchet disc being so proportioned that movement of said arm the full length of said slot moves said disc at least the distance of one tooth.
11. In a permutation lock, in combination, a locking disc, a ratchet disc secured thereto, pawl mechanism for operating said ratchet disc, a face plate having a slot therein, an arm projecting through said slot and carrying said pawl mechanism, and said ratchet disc being so proportioned that movement of said arm the full length of said slot moves said disc a distance greater than the distance of one tooth.
12. In a permutation lock, in combination, a locking disc, a ratchet disc secured thereto, pawl mechanism for operating said ratchet disc, a face plate having a slot therein, an arm projecting through said slot and carrying said pawl mechanism, said ratchet disc being so proportioned that movement of said arm the full length of said slot moves said disc a distance greater than the distance of one tooth, and said slot and said arm being provided with means for indicating thereon the movement of said disc through one tooth and multiples thereof.
13. In a permutation lock having a plu-
 85 rality of locking discs, in combination, means operable from the face of the lock for setting each of the discs to unlocking position, a plurality of mutilated gears carried with the discs, respectively, a lever extending through the face of the lock, a plurality of gears rotatably carried thereby and adapted to engage the mutilated gears, respectively, and means operable from the face of the lock to rotate the second named gears.
14. In a permutation lock having a plu-
 90 rality of locking discs, in combination, means operable from the face of the lock for setting each of the discs to unlocking position, a plurality of gears carried with the discs, respectively, a lever extending through the face of the lock, a plurality of gears rotatably carried thereby and adapted to engage the gears, respectively, means to control the relative rotation between the respective gears, and means operable from the face of the lock to rotate the second named gears.
15. In a permutation lock, in combination, a plurality of locking discs, a plurality of mutilated gears carried therewith, respectively, a lever pivoted within the lock and extending through the face thereof, a shaft journalled on the lever, a plurality of gears mounted on the shaft and adapted to mesh, respectively, with the mutilated gears, a shaft extending through the face of the lock, manual means to turn the shaft carried therewith and driving connections between the two shafts and operable when the respective gears are in mesh.
16. In a permutation lock, in combination,

a bolt, a locking bar mounted for longitudinal sliding movement parallel to the bolt, locking mechanism operable on the locking bar, means operable from the rear of the lock to withdraw the bolt independently of the locking mechanism, means to retract the locking bar operable from the face of the

lock, resilient means to return the locking bar and project the bolt, cooperating means between the bolt and locking bar operable upon retraction of the locking bar and means normally preventing operation of said retracting means. **10**

ANDRÉ JANER.
